UNITED STATES PATENT OFFICE.

THOMAS E. BADEN, OF WASHINGTON, D. C., ASSIGNOR OF ONE-HALF TO
BENJAMIN F. GUY AND HENRY O. TOWLES, OF SAME PLACE.

FILE-HOLDER.

SPECIFICATION forming part of Letters Patent No. 361,975, dated April 26, 1887.

Application filed June 2, 1886. Serial No. 203,896. (No model.)

To all whom it may concern:

Be it known that I, THOMAS E. BADEN, a citizen of the United States, residing at West Washington, in the District of Columbia, have 5 invented certain new and useful Improvements in File-Holders; and I do hereby declare the following to be a full, clear, and exact description of the invention, such as will enable others skilled in the art to which it appertains to make 10 and use the same.

This invention relates to that class of file-holders which are placed in cells or pigeon-holes in a case and constructed to be drawn out therefrom and returned, as desired; and 15 the invention consists in certain improvements in the construction of the removable file-holder, as hereafter described and claimed.

In the accompanying drawings, Figure 1 represents a side view of a file-holder provided 20 with my improvement. Fig. 2 is a sectional rear end view of the same.

A designates the base of the file-holder, to which is fastened the upright front board, B.

C indicates the side pieces, firmly secured to 25 the base and front board, and provided with the longitudinal slots c.

The follower-board D, for closing against the files placed in the holder, is beveled at its lower end, as seen at a, and has fastened to its 30 rear side a plate, d, having a handle, b, and being beveled at its lower end to correspond with the beveled board D, as shown, so that it projects somewhat lower than the end of said board, and has an edge, e, which is presented diagonally to the floor E.

The follower D is provided with the retaining pins or studs f, which pass through the slots c and loosely secure the follower to the side pieces. When the follower is braced in 40 position, its edge e bears against the floor and

the pins f press upward against the edges g, forming the upper sides of slots c. At or near the rear ends of slots c a short upward curve, h, is formed in each of said slots for the purpose of setting the follower in an inclined position at the rear end of the holder, as may be desired, when the holder is filled or nearly filled with papers and a person is examining them. 45

The follower, being at the rear end of the device, is turned to an inclined position rearward, with its foot resting against the inclined surface i on the base, as indicated by dotted lines in Fig. 1, such movement being facilitated by the curves h in the slots, which also serve to sustain the follower in its position. 50

The follower, constructed with the beveled foot and adapted to press upward against the side pieces when braced in position, may be firmly fixed at any point along the holder, and is readily released. 55

I am aware of certain file-holders heretofore in use having followers or movable file-boards loosely connected with slotted rails and constructed to be turned to a relatively-inclined position; but these devices do not fully answer 60 the purposes of my invention, and therefore 65

I claim—

In a file-holder, fixed side pieces having longitudinal slots provided at their rear ends with upward curves h, base A, having at its 70 rear end a beveled or inclined portion, i, and a follower having retaining-pins and provided with a beveled foot, substantially as set forth and described.

In testimony whereof I have affixed my signature in presence of two witnesses. 75

THOS. E. BADEN.
